LUBRICATING JOURNAL BOX FOR CAR AXLES

Filed Feb. 16, 1921

Inventor

Harry V. Boddy

By Watson E. Coleman
Attorney

UNITED STATES PATENT OFFICE.

HARRY V. BODDY, OF MARCELINE, MISSOURI.

LUBRICATING JOURNAL BOX FOR CAR AXLES.

Application filed February 16, 1921. Serial No. 445,426.

To all whom it may concern:

Be it known that I, HARRY V. BODDY, a citizen of the United States, residing at Marceline, in the county of Linn and State 5 of Missouri, have invented certain new and useful Improvements in Lubricating Journal Boxes for Car Axles, of which the following is a specification, reference being had to the accompanying drawings.

10 In a device of this character it is the purpose to provide a lubricator, wherein through the medium of vibrating movements and a capillary attraction, lubricant is fed to the journal along strands of wool 15 waste.

Another purpose involves the provision of means for carrying the wool waste in the journal box and holding it adjacent the journal.

20 Still a further purpose consists in the provision of means for steadyng and holding the journal in the journal box.

While the design and construction at present illustrated and set forth is deemed 25 preferable, it is obvious that as a result of a reduction of the invention to a more practical form for commercial purposes, the invention may be susceptible of changes, and the right to these changes is claimed, provided they are comprehended within the 30 scope of what is claimed.

The invention comprises further features and combination of parts, as will be herein-after set forth, shown in the drawings and 35 claimed.

In the drawings:—

Figure 1 is a longitudinal sectional view through the box, showing the journal mounted therein, and illustrating the lubricating means therein.

Figure 2 is a transverse sectional view on line 2—2 of Figure 1.

Figure 3 is a sectional view through the journal box, showing the journal, the lubricating means and the top bearing for the journal in elevation.

Figure 4 is a detail perspective view of the retaining plate 19.

Figure 5 is a detail perspective view of the bearing plate 16.

Referring to the drawings, 1 designates the journal boxing as a whole, the lower portion 2 of which contains the lubricant 3 to be applied to the journal. A car axle 4 55 is illustrated and it has its journal 5 engaging the boxing. The opposite ends of the

journal have shoulders 6 and 7, between which the semi-cylindrical plate 8 is operable. This plate is provided with a plurality of perforations 9, through which strands of wool waste securely engage. In other words the plate 8 constitutes a carrier for the wool waste, which engages the interior of the bottom of the cavity 2 of the box. The upper ends of the strands of the wool waste engage between the carrier and the cylindrical surface of the journal, and through the medium of capillary attraction, the lubricant feeds to the journal, and lubricates the surface thereof.

70 The plate or carrier 8 has lateral flanges 10, which are engaged by the bolts 11. The bolts 11 extend upwardly and through the upper wall of the boxing, and engaged with their upper ends are springs 12. These 75 springs bear in recesses 13 of the upper wall of the boxing, there being nuts and plates 14 and 14^a engaged with the upper ends of the springs, and by means of the cotter pins 15, the nuts are prevented from unscrewing.

Engaged with the upper part of the chamber is a bearing plate 16, which has its semi-cylindrical inner surface 17 engaged with the journal between the shoulders 6 and 7. The outer face of the bearing 16 is angular as shown at 18, to conform to and engage with the retaining plate 19. This retaining plate is interposed between the bearing plate 16 and the upper wall of the 80 boxing. One end of the retaining plate is engaged by the bolts 11 toward the inner portion of the journal, while the shoulders 20 at the opposite end of the retaining plate are engaged by the other bolts near the outer portion of the journal, thereby anchoring the retaining plate in position. The inner end of the bearing plate has a shoulder 21, which is engaged by inner 85 bolts 11, thereby assisting in holding the bearing plate in position.

The journal box is of the general or conventional construction, hence the inner end of the journal box is provided with guides 22 for the usual plate sections 23, which are 90 provided with semi-circular grooves or cut away portions, which fit upon the journal, to keep out dirt and grit. The upper plate section acts by gravity, whereas the lower plate section bears against the bottom 24 of the guides, though it is obvious that a suitable spring may be interposed between the 95

bottom, and the under part of the roller to retain it in position.

This improved lubricating journal box for car axles may be used on engine trucks, 5 trailer boxes as well as passenger and freight service equipment, or upon any form of journal where lubrication is necessary to insure easy running, and to reduce the wear and friction on the moving parts. Any 10 suitable waste may be used in the journal box, either wool or cotton waste, ball wicking or any form of waste that would tend to decrease the cost and accomplish the same purpose as wool waste.

15 The invention having been set forth, what is claimed as being useful is:

1. In a device for the purpose indicated, the combination with an axle journal, of a journal boxing therefor, the lower portion 20 constituting a lubricant container, a wool waste carrier comprising a semi-cylindrical perforated plate engaging the under part of the journal, wool waste securely anchored in the perforations and being suspended in 25 the container and engaged between the plate and the journal for feeding lubricant thereto, said plate having lateral flanges, bolts yieldingly anchored in the upper wall of the boxing and connected to the lateral 30 flanges for suspending said plate, a bearing plate for the upper part of the journal, a retaining plate between the upper wall of the boxing and the bearing plate, said bearing and retaining plates having operative 35 connections with the bolts to hold said plates in position.

2. In a device for the purpose indicated, the combination with an axle journal, of a journal boxing therefor, the lower portion 40 constituting a lubricant container, a wool waste carrier comprising a semi-cylindrical perforated plate engaging the under part of the journal, wool waste securely anchored in the perforations and being sus- 45 pended in the container and engaged between the plate and the journal for feeding lubricant thereto, said plate having lateral flanges, bolts yieldably anchored in the upper wall of the boxing and connected to the 50 lateral flanges for suspending said plate, a bearing plate for the upper part of the journal, a retaining plate between the upper

wall of the boxing and the bearing plate, said bearing and retaining plates having operative connections with the bolts to hold 55 said plates in position, said connections comprising shoulders at the opposite ends of the journal, between which the bearing plate engages, said bearing plate and the retaining plate having shoulders to be engaged by the bolts to prevent movement of 60 the plates.

3. In a lubricating journal box, an axle journal, a journal box therefor having means at one end for the reception and support of an axle, a bearing plate in the boxing for engagement with said journal, a retaining plate between the upper wall of the boxing and the bearing plate, a lubricant wool waste feed for the journal including a plate, tensioned bolts operatively mounted on the upper wall of the boxing and operatively connected to the plate carrying the wool waste feed, said bolts engaging the sides of the bearing plate, acting to 70 hold the bearing plate in place, and abutments carried by the retaining plate and operatively engaging with the bolts, not only to hold the retaining plate in position with relation to the bearing plate, but at 75 the same time acting to hold the bearing plate in position.

4. In a lubricating journal box, an axle journal, a journal boxing therefor, the lower portion thereof constituting a lubricating container, a lubricant feeding device mounted under and engaging the journal, a bearing plate above and engaging the journal, a retaining plate between the bearing plate and the upper wall of the boxing, 80 means for adjustably suspending the lubricant feeding device in operative position in the boxing, said supporting means for the lubricant feeding device including hangers, said retaining plate having abutment means 85 operatively connecting with said hangers, for not only preventing endwise movement of the retaining plate, but also acting to hold the bearing plate in operative position 90 on the journal.

In testimony whereof I hereunto affix my signature.

HARRY V. BODDY.
